Primary Examiner — Mark A Goodwin(74) *Attorney, Agent, or Firm* — Daryl R. Wright; Greg Carr(57) **CLAIM**

We claim the ornamental design for a model vehicle track tread, as shown and described.

DESCRIPTION

FIG. 1 is an upper, left, front perspective view of a model vehicle track tread showing our new design;
FIG. 2 is a front side elevation view thereof;
FIG. 3 is a rear side elevation view thereof;
FIG. 4 is a right side elevation view thereof;
FIG. 5 is a right side elevation view thereof;
FIG. 6 is a top plan view thereof;
FIG. 7 is a bottom plan view thereof;
FIG. 8 is an enlarged portion of FIG. 1 showing an upper, left, front perspective detail view thereof;
FIG. 9 is an enlarged portion of FIG. 4 showing a right side detail view thereof; and,
FIG. 10 is an enlarged portion of FIG. 5 showing a left side detail view of the model vehicle track tread.
In the drawings, the broken lines illustrate portions of the model vehicle track tread that form no part of the claimed design.
